COLLAR OR SIMILAR ARTICLE

Michael A. Greene, New York, N. Y.

Application February 19, 1957, Serial No. 44,913

Term of patent 14 years

(Cl. D3—16)

Fig. 1 is a front view of a collar or similar article showing my new design.

Fig. 2 is a rear view thereof.

Fig. 3 is a plan view of the collar in open position.

I claim:

The ornamental design for a collar or similar article, substantially as shown.
